INFLATABLE BALL

David Levinson, Chicago, Ill., assignor to Standard Sports Mfg. Co., Chicago, Ill., a corporation of Illinois

Application August 14, 1935, Serial No. 36,113

6 Claims. (Cl. 273—65)

The invention relates generally to balls and more particularly to an inflatable ball such as a basket ball, volley ball, soccer ball, or the like comprising broadly a cover with an inflatable bladder.

5 The general object of the invention is to provide an inflatable ball having a new and improved form of lacing for an opening in the cover of the ball, through which the bladder may be inserted, the lacing being such that it provides proper balance for the ball and does not project beyond the normal surface of ball to affect the accuracy of the bounce of the ball when struck at that point.

10 15 It is also an object to provide an inflatable ball of the foregoing character in which the cover may be adequately reinforced adjacent the lacing but without employing any stitching exposed on the outer surface of the cover and thus subject to wear.

20 25 A still further object is to provide an inflatable ball having a lacing of such character that the lace is protected against wear from abrasion by external contact and hence may be of smaller size than those heretofore employed.

Still another object is to provide an inflatable ball having the foregoing construction and provided with a flap extending across the opening to insure complete closure thereof even though there is a tendency to gap.

30 35 Other objects and advantages will become apparent from the following description taken in connection with the accompanying drawings, in which:

Figure 1 is an elevational view, partially in section, of a ball embodying the feature of the invention.

Fig. 2 is an enlarged fragmentary view of the exterior of the ball to show the lacing.

Fig. 3 is a view similar to Fig. 2 but showing the interior of the cover.

Fig. 4 is a sectional view taken along the line 4—4 of Fig. 2.

Fig. 5 is a sectional view taken along the line 5—5 of Fig. 2.

Fig. 6 is a view similar to Fig. 3 but of a modified form of ball.

Figs. 7 and 8 are views similar to Figs. 4 and 5 but of the modified form.

Figure 9 is another view of the modified form of the ball shown in Figures 7 and 8.

In inflatable balls, such as basket balls, volley balls, or soccer balls, one of the common forms as heretofore made employed a lacing for closing the opening for the insertion of the bladder,

the lacing extending over the outer surface of the ball for short distances in passing from one aperture to another in the cover. Such a form of lacing had a number of disadvantages, the chief of which was that the lacing materially affected the bounce of the ball, if the ball struck on the lacing. Thus, it tended to deaden the bounce when so struck, and to make the bounce inaccurate as to direction. The lacing was also subject to wear due to abrasion by the surface struck, and as a result a fairly heavy lace was required. Because of the stress on the cover of the ball around the apertures through which the lacing passed, pieces of reinforcing, such as strips of leather, were positioned on the interior of the cover, and were held in place by stitching extending through to the outer surface of the ball. This stitching was also subject to wear, and after a time would break and loosen the reinforcing strips. The lacing, in this type of ball, caused the edges of the cover at the opening to lie flat. This, however, necessitated cutting away part of the cover at these edges for the length of the opening, since where the cover was seamed the edges were turned inwardly.

A ball of the so-called "laceless" type was developed, in which no lacing at all was employed. In this type, a portion of one of the seams of the cover section was left unsewed, or loosely sewed, to allow for insertion of the bladder. The latter was secured to the interior of the cover at a point spaced from said seam, where there was an opening for the inflation of the bladder, a suitable form of valve structure being employed therewith. After the bladder was inserted, the open seam was closed by stitching or by tightening the stitches already there. Such a construction avoided wear on a lacing and did not affect the bounce of the ball. But it meant that the ball had to be returned to the factory whenever the bladder had to be replaced or repaired, because users of the ball were not sufficiently skilled or did not have the proper equipment to resew the ball. Such a ball also had the disadvantage of not being properly balanced, in that there was not part of the structure to counterbalance the valve structure.

A ball embodying the features of the present invention has the advantages of both of the above-mentioned types of balls without their attendant disadvantages. Generally, the preferred embodiment comprises a lacing for drawing two sections of the cover together in such a manner that the edges of the sections turn in-

wardly to provide an external groove in which the external portions of the lacing wholly lie. The lacing will thus not affect the bounce of the ball, since it will not come in contact with the 5 surface struck, and also will not be subjected to abrasion. The lacing therefore may be somewhat smaller than the lacings heretofore employed, so that it may readily lie within the groove. The lacing also permits access to the 10 bladder so that the latter may be readily replaced without necessitating return of the ball to the factory. The apertures in the cover sections open into the external groove, and may be reinforced by internal strips of leather. To attach 15 such strips to the cover, a line of stitching through the cover may be placed nearer the edge of the sections than the apertures, so that this stitching lies within the groove and is thus protected from wear. A second line of stitching may 20 also be used on the opposite side of the apertures and such stitching may extend only through the lining and not to the exterior of the cover. Wear due to abrasion is thus avoided on 25 the stitching as well as on the lacing. With this type of lacing, the necessity of cutting away the cover sections at the opening is avoided.

As shown in the drawings, the preferred embodiment of the ball comprises a cover preferably made of a plurality of sections 10 of leather, a 30 lining 11 usually of heavy fabric, and a bladder 12. The lining 11 is also preferably made in sections similar to the cover and the lining sections and cover sections are stitched together at their edges. The cover sections are preferably 35 seamed together by stitching 13 (see Fig. 3) which extends through and turns the edges of the respective cover sections inwardly in side-by-side relation, the stitching 13 also extending through the lining sections. Part of one such seam is 40 left unsewed to provide an opening for the insertion of the bladder 12, and is closed by means of a lacing indicated generally at 14. In order to balance the ball, the valve structure, shown at 15 in Fig. 1, for the inflation of the bladder, 45 is positioned diametrically opposite the lacing 14, so that the two with the related parts counter-balance each other.

The lacing is so placed in the cover as to turn the edges of the cover sections inwardly. To 50 this end, a row of equally spaced apertures 16 are provided in each cover section closely adjacent the edge thereof with the rows extending the full length of the bladder insertion opening. The lacing extends through the apertures 16 in such 55 a manner that the inner portions of the lacing extend longitudinally of the opening and the exterior portions of the lacing extend transversely of the opening. Thus, the transverse stress of the lacing causes the edges of the cover sections 60 to turn inwardly, and the necessity of cutting away the edges of the cover sections at the opening is avoided.

To lace the opening in this manner, the mid point of the lacing is positioned on the interior 65 of the ball at one end of the opening, and the ends of the lacing pass out through the adjacent aperture 16. If it is desired to employ two shorter laces they may be knotted together, as at 70 17, and the knot is thus the mid point. The two ends of the lace are then carried transversely of the opening on the exterior of the ball and pass back through the two apertures 16. Internally, 75 the lace is carried longitudinally of the opening on the respective sides thereof and out through the next pair of apertures 16. Externally the

ends of the lace are again carried transversely to reenter the cover through the opposite aperture. This is repeated until the opening is completely laced. The lacing thus has a pair of external portions 18 extending transversely of the 5 opening at each pair of opposed apertures 16, and a pair of internal portions 19 extending parallel to the opening from each aperture to the next in its row.

At the end of the opening opposite the end 10 where the lacing was started, the ends of the lace, after they enter the cover through the last pair of opposed apertures 16, are carried out between the two cover sections and then longitudinally of the opening, preferably passing between the respective portions 18, as shown at 20 in Figs. 2, 4 and 5. At the starting end of the opening, the portions 20 may be tucked under both portions 18, which is sufficient to hold the lacing in place. At the ends of the opening, the inturned edges of the 20 cover sections may be notched as at 25 to provide space for the knot 17 at one end and the in-turned portions of the lace at the other end.

When laced in this manner, and the lacing is drawn tight, the edges of the cover sections turn 25 inwardly, as they do at the seams because of the stitching 13, and an external groove, indicated at 21, is formed on the ball by the bending of the cover sections. This groove has a width 30 slightly greater than the space between the opposed rows of apertures 16 and is of such size that the external portions 18 and 20 of the lacing lie wholly within the groove. They thus lie within the normal perimeter of the ball and will not be subjected to abrasion by the surfaces which 35 the ball strikes when in use. Since the lacing is not subjected to wear from this source, it may be lighter or of smaller cross section than the former type of lacing which was subject to such wear. It therefore will fit more snugly in the 40 groove than if it were larger.

Another feature of the invention resides in the provision of reinforcing strips for the cover adjacent the aperture 16, similar to the strips used in former types of laced balls, but sewed in such 45 a manner that the stitching will not be exposed at points where it can be worn by abrasion. As shown herein, said strips comprise elongated pieces of leather 22 positioned internally of the lining 11 and extending from the edge of the 50 opening outwardly therefrom beyond the apertures 16. To secure the reinforcing strips 22 to the cover, each strip is sewed to the cover by a line of stitching 23 located between the edge of the cover section and the row of apertures 16, 55 and by a second line of stitching 24 on the other side of the row of apertures. The line of stitching 23 preferably extends clear through the cover, but on the exterior, it is located within the groove 21 and under the lacing so that it is protected 60 against abrasion. The other line of stitching 24 extends merely through the lining 11 so that it is not exposed on the exterior of the ball.

When the ball is inflated, the stress on the lacing is transmitted to the cover reinforced by the 65 pieces 22. However, should such stress tend to draw more on the lining than the cover because of the fact that the reinforcing pieces are not secured to the cover proper beyond the apertures 16, the stress is in turn transmitted to the cover 70 proper by the lining because the lining is made in sections secured at their edges to the cover. There will thus be no tendency for the lacing to draw the lining tighter than the cover.

In the modified form of ball shown in Figs. 75

6, 7 and 8, I have provided a construction whereby full closure of the opening is insured, even though there is a tendency for the opening to gap upon inflation of the ball. To this end, a 5 flap 30, preferably of leather, is secured adjacent the opening inside of the cover and extends across the opening. Thus, even though there should be a tendency for the opening to gap, the flap 30 constitutes a closure therefor. Preferably the flap 30 is secured to one of the reinforcing pieces 22 by the line of stitching 24 which thus also secures the flap to the lining 11. The flap may be of the same length as the opening, and to avoid causing a bulge by the 10 flap, the edges of the cover sections, together with the lining and reinforcing pieces, may be cut away as at 31 for the length of the opening. Thus, the flap will lie within the cut-away area to avoid bulkiness on the inside of the ball at 15 the opening.

From the above description, it will be apparent that I have provided an inflatable ball possessing the advantages of both the old type of laced ball and the so-called "laceless" ball without the disadvantages thereof. The lacing will not cause inaccuracy of the bounce of the ball when struck at that point, since it lies within the normal perimeter of the ball, but does provide proper balance for the ball by counterbalancing the 20 weight of the valve structure. Since the lacing lies within the normal perimeter of the ball, it is not subject to abrasion, so that a lace of relatively small cross section may be used. The apertures for the lacing may be reinforced by strips 25 sewed to the cover in such a manner that the stitching is also protected against abrasion.

I claim as my invention:

1. In an inflatable ball, a cover having a 30 bladder-insertion opening with a plurality of spaced apertures in the cover arranged along the respective sides of and closely adjacent said opening to receive a lacing, a lining within the cover, a lacing extending through said apertures and drawn tight to turn the edge portions of the 35 cover inwardly at said opening and thereby forming an external groove in which the lacing lies, and a pair of reinforcing pieces located on the interior of the lining along the respective sides of the opening, each of said pieces being secured by two lines of stitching, one of said lines extending through the cover but within said groove, and the other line extending merely through the lining.

2. In an inflatable ball, a cover having a 40 bladder-insertion opening with a plurality of spaced apertures in the cover arranged along the respective sides of and closely adjacent said opening to receive a lacing, a lining within the cover, a lacing extending through said apertures and drawn tight to turn the edge portions of the 45 cover inwardly at said opening and thereby forming an external groove in which the lacing lies, and a pair of pieces for reinforcing the cover at

said opening and located interiorly of the lining, said pieces being secured in place by stitching extending through the cover only within said groove.

3. In an inflatable ball, a cover having a 5 bladder-insertion opening with a plurality of spaced apertures in the cover arranged along the respective sides of and closely adjacent said opening to receive a lacing, a lining within the cover, a lacing extending through said apertures 10 and drawn tight to turn the edge portions of the cover inwardly at said opening and thereby forming an external groove in which the lacing lies, and a pair of pieces for reinforcing the cover at said apertures and located interiorly of the lining, each of said pieces being secured in place by a line of stitching extending through the cover and located between said apertures and said opening whereby the stitching lies within said groove, and a line of stitching beyond the 15 apertures but extending only through the lining.

4. An inflatable ball comprising, in combination, a cover comprising a plurality of sections secured together at their edges, a lining for said cover comprising a plurality of sections similar 25 to the cover sections and secured to the edges thereof, two sections of the cover being left unsecured to each other for a given length to provide a bladder-insertion opening, a lacing for closing said opening, and a pair of reinforcing 30 pieces for reinforcing the cover adjacent said lacing, each of said pieces being held in place by a line of stitching extending only through the lining, the stress on each of said pieces caused by the lacing being transmitted to the lining by 35 said line of stitching and thence to the cover by the securement of the lining sections to the cover sections.

5. An inflatable ball comprising, a cover having a bladder-insertion opening, a lacing for 40 closing said opening and constructed to turn the edges of the cover at said opening inwardly, and a flap secured to the cover on the inside thereof along one side of the opening and extending across the opening to insure closing thereof, the 45 inturned edges of the cover being cut away for a depth at least equal to the thickness of the flap so that the flap may lie within the cut-away area to avoid bulkiness.

6. An inflatable ball comprising, a cover having a bladder-insertion opening, a lining within the cover, a lacing for closing said opening and constructed to turn the edges of the cover at said opening inwardly, a pair of reinforcing pieces for reinforcing the cover along said edges adjacent 55 the lacing and secured to the cover adjacent said edges and to the lining alone by a line of stitching laterally beyond the lacing, and a flap extending across the opening on the inside of the ball and secured at one edge by said line of 60 stitching, the other edge of the flap being free.

DAVID LEVINSON.
